UNITED STATES PATENT OFFICE.

JAMES G. STEWART, OF MINNEAPOLIS, MINNESOTA.

ROLLING WINDOW SCREEN.

Application filed January 7, 1925. Serial No. 1,031.

The object of the invention is primarily to provide a window screen which will always be in nesting relation except when in use and further to provide means for tensioning it and effectively guiding it at the side edges.

With this object in view, the invention consists in the construction and combination of parts of which a preferred embodiment is illustrated in the accompanying drawings, 10 wherein:

Figure 1 is a front elevational view of a window frame showing the application of the invention.

Figure 2 is a central vertical sectional view 15 on the line 2—2 of Figure 1.

Figure 3 is a detail view illustrating a section of the side guides.

Figure 4 is a detail elevational view on an 20 enlarged scale of a section of a side edge of the screen.

The invention is designed for use so that the window opening may be screened at the time of lowering the top sash 1 or raising the bottom sash 2, the screen cooperating 25 with the top sash being carried in a housing 3 disposed at the top of the window frame and that for cooperation with the lower sash being enclosed in a housing 4 disposed at the bottom of the window frame. So far as 30 the screens themselves are concerned, their construction is identical and a description of one will suffice for both.

In the housing is mounted a spring-actuated roller 5 on which the screen 6 is reeled, 35 being secured at one end to the roller and at the other end being provided with a metal plate 7 secured to the lower rail of the lower sash or the top rail of the upper sash, depending on whether it be used as a screen member for the upper or lower sash.

On the sides of the window frame are 40 mounted the guides 8 which are of tubular form and provided with ears 9 for the reception of screws 10 to secure the guides in place.

45 The guides are provided with longitudinal

slots 11 traversed by the edges of the screen and interior to the guides the marginal bindings 12 are provided, these consisting of spiral springs, with the separate coils of which the marginal edges of the screen 6 are 50 engaged.

The springs 12 are tensioned sufficiently to provide enough transverse strain on the screen 6 to retain it in flat condition and being dimensioned according to the tubular 55 guides, always retain the marginal edge of the screen in engagement with the guides, the springs sliding through the guides as the screens are reeled upon or unreeled from the rollers 5.

The invention having been described, what is claimed as new and useful is:

1. A rolling window screen comprising a spring-actuated roller, a screen having one end connected with the roller and adapted for connection at the other end with the rail of a window sash, side guides for the marginal edges of the screen, and longitudinally extensible and contractible binding elements traversing the guides and engaged with the 70 marginal edges of the screen.

2. A rolling window screen comprising a spring-actuated roller, a screen having one end connected with the roller and adapted for connection at the other end with the rail of a window sash, side guides for the marginal edges of the screen, and longitudinally extensible and contractible binding elements traversing the guides and engaged with the marginal edges of the screen, said binding 80 elements consisting of spiral springs with the coils of which the marginal edges of the screen are engaged and the guides consisting of tubular members cross sectionally conforming to the springs and longitudinally slotted for the reception of the marginal edges of the screen.

In testimony whereof he affixes his signature.

JAMES G. STEWART.
